LIQUID FUEL VAPORIZER

William A. Clements, Glendale, Calif.

Application June 1, 1946, Serial No. 673,878

20 Claims. (Cl. 48—107)

1 The present invention relates generally to vaporization of liquid hydrocarbons and more particularly to means for controlling such vaporization to the end that more accurate burner control may be obtained.

Vaporization of liquid hydrocarbon is of great importance in various industries for supplying gaseous fuel to industrial furnaces and ovens and may be found indispensable in places where the supply of natural or commercial gas is either insufficient, non-uniform, or both.

The principal object of this invention is to provide a vaporizing system of this character which will operate over a considerable range to supply the amount of heat required to maintain a number of burners in operation and which will, under all operating conditions, produce a combustible mixture of uniform predetermined character or quality.

Other objects and the many advantageous features of the invention will be apparent from the following detailed description and by referring to the accompanying drawings wherein:

Fig. 1 is a general view of a fuel vaporizing system embodying the invention;

Fig. 2 is a plan view, partly in section, of the generator of the system shown in Fig. 1;

Fig. 3 is a cross-sectional view of a modified form of generator used in the system shown in Fig. 1; and

Fig. 4 is a sectional detail view, on a larger scale, of certain parts of the generator of Fig. 3, the importance of which is hereinafter fully explained.

The structure of the invention, in the form illustrated, is designed to supply gaseous fuel to a battery of burners (not shown) through a manifold 1. A non-pulsating flow of air from a blower or other equivalent source is supplied to the manifold through a pipe 2, terminating in a contracted orifice or nozzle 3. The latter is seated within a casing 4, having a contracted passage 5 in axial alignment with said nozzle, and it is noticed that the area of the passage continuing through the portion of the casing extending to and connecting with the manifold 1 gradually increases, thereby to form a Venturi tube 6 at this point.

A vapor generator 8 is shown placed below the casing 4 and it communicates therewith through a pipe connection 7. The generator comprises a substantially oval casing, circular in horizontal cross section. The casing is, by a plate 10, divided into an upper vaporizing chamber 11 and a lower combustion chamber 12. It is furthermore

important to note that the central portion of the plate 10 is recessed to form a dome 10a rising into the upper chamber.

In the bottom of the generator is seated a burner block 13. A pipe-line 14 is cut into the manifold 1, at 15, and it extends to a position directly below the burner block, at which point it is fitted with a burner nozzle 16.

In order to put the system into operation, it is 10 first required to heat the generator casing, and this may be done by directing raw gas past a valve 17 into the lower, horizontal portion of the pipe-line 14, substantially as shown, and to ignite this gas at the nozzle 16.

15 The air supply to the casing 4, which conveniently may be termed the mixing head of the system, is at the same time turned on, and the air rushing into the manifold creates and maintains a state of compression therein.

20 The flame from the burner nozzle 16 rises through the burner block 13 into the dome 10a and around this block into the lower, combustion chamber 12. It is now noticed that a series of tubular members 20 are vertically seated in the plate 10 and that they extend nearly to the top and bottom of the generator casing. It is important to note that the flame or heat descending into the lower chamber, in the manner just described, rises through these members to pass 25 through the upper chamber 11 around the dome 10a and through the pipe connection 7 into the mixing head 4.

25 Liquid fuel from a convenient source of supply is admitted through a pipe 22 to a float chamber 23 when, after a short period of time, the generator has been sufficiently heated for vaporization purposes. The fuel flows through a pipe connection 24 into the generator and through the middle section plate 10, over the top of which it 30 spreads to form thereon a pool, the surface level of which is controlled from the float chamber 23. Because the plate 10 and the dome 10a become intensely heated, it is found that a portion of the liquid fuel of the pool becomes vaporized and is 35 drawn up through the mixing head 4 and, intermixed with air, through the manifold to the burners.

40 During this initial firing operation, when the air flow through the pipe 2 starts, it has been 45 found that a portion of the air under pressure within the manifold commences to flow through the pipe-line 14 to the burner 16 and that the air passing through the mixing head becomes more and more saturated with fuel vapor from the 50 generator. As soon as the proper ratio of vapor-

ized fuel to air has been reached, it is found that the intense heat of this mixture will be sufficient to maintain combustion within the generator sufficiently for vaporizing purposes and so to make it possible to turn off the raw gas supply. The system now functions entirely on air and vapor mixture and the amount of heat developed and the rate of flow of vaporized fuel passing through the manifold to the burners is in proper proportion to the flow of air through the mixing head.

It is customary in practice to regulate the air flow through the pipe 2 manually or by remote temperature control, and the system will continue automatically to supply a required flow of uniformly mixed air and vaporized fuel through the manifold. And as this mixed air and vapor flow is accelerated, it tends to increase the pressure within the manifold, thereby to increase the flow of pre-mixed fuel passing to and through the generator burner, in turn correspondingly increasing the rate of fuel vaporization within the generator.

As the fuel vaporization rate increases or decreases, it is found that the liquid level controller within the float chamber correspondingly varies the liquid fuel supply to the generator, thereby to maintain a substantially uniform volume of fuel within the generator at the same liquid level.

From the foregoing description, it is seen that the generator becomes quickly sufficiently pre-heated by the flame of the burner 16 to vaporize fuel on the middle section plate 10. But it is important to note that the flame, or the super-heated gases rising from the flame do not pass directly through the liquid fuel as in other systems that have come to my notice, but flow through the tubular members 20 into the upper chamber of the generator, above the liquid fuel surface. Also that, in passing through this upper chamber, the rising vapor becomes more intensely heated and more completely vaporized by contact with the surface of the dome 10^a. In order further to induce complete vaporization, I have shown the members 20 closed at the top and made with orifices or jets 19 laterally directed from one side of the members, thereby to produce a whirling movement of the combining vaporized material within the chamber, thus preventing heavy oil vapor from passing in to pipe 7 until completely vaporized and super-heated.

In the manifold, below the point 15, may be placed a condensate trap 27, and a pipe-line 28 extends from this trap to the fuel supply pipe 24. It is noticed that the pipe-line 28 is shaped to form a U-seal which, when it becomes filled with condensate or liquid fuel, prevents return of air-gas mixture from the manifold to the generator. Once the system is in full operation, this condensate return system may remain dormant, but when first starting and all piping and the manifold are cold, it is generally necessary to provide such condensate return. As a safety relief in the event of excess pressure within the generator, I prefer to cut a conventional type of poppet relief valve 30 into the upper chamber of the generator. A butterfly valve 33 is cut into the pipe connection above the valve 31 to control the flow to the mixing head 4 and thereby to provide additional means for regulating the flow of vaporized fuel mixture or gaseous fuel to the manifold.

One difficulty in connection with the use of liquid hydrocarbon fuel in any device as ordi-

narily found in commercial use, is that such high degree of heat is required to heat the fuel sufficiently to cause evaporation thereof that carbon may form and deposit within the vaporizing chamber. This is not the case in the device of my invention, as above described, where a much lower temperature of the liquid fuel within the pool is maintained and vaporization thereof is effected by sweeping the combustion products along the surface of the pool before they rise into the mixing head 4.

Where heavy hydrocarbon fuel is used the danger of formation of carbon deposits is even greater, and it may for this reason in such cases be preferable to substitute the type of generator illustrated in Figs. 3 and 4.

The generator casing 40 may in this case remain substantially as above described, and the middle section plate 41 is shown fitted with a dome 42 which also may remain substantially unchanged, although it is shown somewhat smaller in diameter in order to afford additional space for the circulation of the combustion products around the dome.

It is noticed that in this case the tubular members 20 have been modified to show a series of short pipes 43 extending through the plate 41 and bent at right angles above this plate or, for convenient manufacture, fitted with an elbow 44 in which a screw plug is seated. A nozzle 45 extends through the elbow into the passage through the screw plug, and it is noticed that this passage is shaped to form a venturi designed to increase the velocity of the vapors drawn through the nozzle from the surface of the pool which is formed on top of the plate 41. In order to expedite and increase the flow through the nozzle, it is shown made with a downwardly directed portion 47 terminating close to the surface of the liquid in the pool.

With the generator constructed in this manner, it is seen that the superheated combustion products rising through the pipes 43 effectively complete the gasification of the vapors drawn from the surface of the pool, and that for this reason it is not necessary to heat the plate 41 to as high a degree as in the case of the above described generator, and that for this reason all danger of carbon formation is substantially eliminated. It is, however, desirable to make certain that the plate 41 becomes evenly heated over the entire surface thereof, and it is for this reason advisable to mount a flange 48 on the top edge of the burner 13 to extend parallel with the plate 41 nearly to the side wall of the generator casing, substantially as indicated in Fig. 3. With the introduction of this flange it is seen that the flaming combustion products rising from the burner are forced to travel along the under surface of the plate 41 and through the narrow annular space 49 between the flange and the generator casing before reaching the entrance to the pipes 43.

It is possible, should it be so desired, to cut off the generator from the mixing head and to proportionally mix a gaseous fuel with the air passing through the head. Illustrative of such combination, I have shown a conventional 3-way valve 31 cut into the pipe connection 7, and a supply pipe 32 carries gaseous fuel through this valve to the mixing head when the generator is cut off therefrom.

It will be apparent from the foregoing detailed description that I have provided a very complete and highly efficient hydrocarbon vaporizing and

air mixing device for delivering vaporized fuel mixture of uniform quality under all operating conditions to industrial furnaces. I do not, however, limit myself to the specific details and arrangements shown and described, the invention being limited only by the scope of the claims here-to appended.

I claim:

1. A liquid fuel vaporizing device including a generator having an outlet at the top and divided by a center partition into an upper and lower chamber, said partition being centrally recessed to form a dome rising therefrom into said upper chamber thereby to form a reservoir for liquid fuel on top of said partition, a burner below the generator, a fuel supply line to said burner, a passage directing the flame from the burner against the underside of said dome and down into the space below said central partition, passages for carrying combustion products from this combustion space into the chamber above said reservoir, means carrying liquid fuel through the lower chamber of the generator to the reservoir, and means associated therewith for controlling the liquid level within the reservoir.

2. A liquid fuel vaporizing device including a generator having an outlet at the top, said generator being divided into an upper and a lower chamber, a burner below the generator for heating said lower chamber, a fuel line to said burner, a pipe for carrying liquid fuel through the heated lower chamber into the upper chamber to form a reservoir at the bottom thereof, passages for the combustion products from the lower chamber to the space above said liquid reservoir, and means for controlling the liquid level within the reservoir.

3. A liquid fuel vaporizing device including a generator, a plate centrally dividing said generator into an upper and a lower chamber, said plate being recessed to form a dome rising into said upper chamber, there being a reservoir formed on said plate about said dome, a series of tubular members vertically seated in said plate and extending substantially through the two chambers, a burner below the generator, a fuel supply line to said burner, a passage for directing the flame from said burner against the underside of said dome and down into said lower chamber then through the said tubular members, to the space in the upper chamber about said reservoir, means feeding liquid fuel through said lower chamber to the reservoir, and means for controlling the liquid level within the reservoir.

4. A liquid fuel vaporizing device including a generator, a member centrally dividing said generator into an upper and a lower chamber, said upper chamber having an outlet at the top, said member being recessed to form a dome rising into said upper chamber nearly to the top thereof, there being formed a reservoir for liquid fuel on said member about said dome, pipes vertically seated in said central member and extending nearly to the top and bottom of the generator, said pipes being closed at the top and having outlets near the top on one side thereof, a burner below the generator, a fuel line to said burner, a passage for directing the flame from said burner against the underside of said dome down into the lower chamber of the generator, the combustion products passing through said pipes and the lateral outlets at the top thereof into said upper chamber and out through said top opening, the combustion products in passing through the side openings of said pipes being given a

whirling movement about said dome above said reservoir before passing out of said outlet.

5. A liquid fuel vaporizing device including a generator, a member centrally dividing said generator into an upper and a lower chamber, said upper chamber having an outlet at the top, said member being recessed to form a dome rising into said upper chamber nearly to the top thereof, there being formed a reservoir for liquid fuel on said member about said dome, pipes vertically seated in said central member and extending nearly to the top and bottom of the generator, said pipes being closed at the top and having outlets near the top on one side thereof, a burner below the generator, a fuel line to said burner, a passage for directing the flame from said burner against the underside of said dome down into the lower chamber of the generator, the combustion products passing through said pipes into said upper chamber and out through said top opening, the combustion products in passing through the side openings of said pipes being given a whirling movement about said dome above said reservoir before passing out of said outlet, means carrying liquid fuel through said heated lower chamber into said reservoir, and means for controlling the liquid level therein.

6. A liquid fuel vaporizing device including a generator having an outlet at the top, said generator being divided into an upper and a lower chamber, a burner below the generator for heating said lower chamber, a fuel line to said burner, a pipe for carrying liquid fuel through the heated lower chamber into the upper chamber to form a reservoir at the bottom thereof, passages for the combustion products from the lower chamber to the space above said liquid reservoir, means controlling the liquid level within the reservoir, and a relief valve in said upper chamber.

7. A liquid fuel vaporizing device including a generator having an outlet at the top, said generator being divided into an upper and lower chamber, a burner below the generator for heating said lower chamber, a fuel line to said burner, a pipe for carrying liquid fuel through the heated lower chamber into the upper chamber to form a reservoir at the bottom thereof, passages for the combustion products from the lower chamber to the space above said liquid reservoir, said passages being bent at the top to discharge the combustion products along the surface of the liquid in the reservoir, and a nozzle extending into said bent portion of each passage, each nozzle having a downwardly directed portion outside of the passage and extending nearly to the surface of the liquid within said reservoir.

8. In a liquid fuel vaporizing device in combination, a generator divided into an upper vaporizing chamber having a liquid fuel reservoir therein and a lower combustion chamber, a conduit for air under pressure, pipe connection from said upper chamber to said conduit, a burner for heating said combustion chamber, a fuel supply line to said burner, passages for the combustion products through the space above said reservoir to the said pipe connection, and a conduit leading from a point in said air conduit in front of said pipe connection to said burner.

9. In a liquid fuel vaporizing device in combination, a generator divided into an upper vaporizing chamber having a liquid fuel reservoir therein and a lower combustion chamber, a conduit for air under pressure, pipe connection from said upper chamber to said air conduit, a burner for heating said combustion chamber, a fuel sup-

ply line to said burner, passages for the combustion products through the space above said reservoir to the said pipe connection, a conduit leading from a point in said air conduit in front of said pipe connection to said burner, a pipe carrying liquid fuel through the combustion chamber to said reservoir, and means associated with said pipe for controlling the liquid level within the reservoir.

10. In a liquid fuel vaporizing device in combination, a generator divided into an upper vaporizing chamber having a liquid fuel reservoir therein and a lower combustion chamber, a mixing chamber, a pipe carrying air under pressure to said chamber, a pipe connection from said upper chamber to said mixing chamber, a mixed fuel conduit extending from said mixing chamber in axial alignment with said air pipe, a burner for heating said combustion chamber, a fuel supply line to said burner, passages for the combustion products from said combustion chamber through the space above said reservoir to the said pipe connection, a pipe carrying liquid fuel through the combustion chamber to the reservoir, and means associated with said pipe for controlling the liquid level within the reservoir.

11. In a device for supplying vaporized fuel to a battery of furnaces, a manifold leading to said furnaces, a pipe carrying air under pressure to said manifold, a mixing chamber encompassing the adjoining ends of said pipe and manifold, a generator divided into an upper vaporizing chamber having a liquid fuel reservoir therein and a lower combustion chamber, pipe connections from said upper chamber to the manifold, a burner below the generator for heating the combustion chamber, passages for the combustion products from the combustion chamber through said upper chamber and the said pipe connection to the mixing chamber, a conduit for carrying liquid fuel through the combustion chamber into said reservoir, and means associated with said conduit for controlling the liquid level within the reservoir.

12. In a liquid fuel vaporizing device in combination, a generator horizontally divided into an upper vaporizing chamber having a liquid fuel reservoir therein and a lower combustion chamber, a conduit for air under pressure, a pipe connection from said upper chamber to said conduit, a burner below the generator for heating said combustion chamber, conduits for carrying the combustion products from the combustion chamber through the space above said reservoir to the pipe connection, a pipe carrying gaseous fuel to said pipe connection, and a valve controlling flow of fuel from the upper chamber or from said gaseous fuel pipe to said air conduit.

13. In a liquid fuel vaporizing device in combination, a generator divided by a horizontal partition into an upper vaporizing chamber and a lower combustion chamber, the center portion of said partition being recessed to form a dome rising into said upper chamber and providing a reservoir about said dome, a conduit for air under pressure, a pipe connection from said upper chamber to said conduit, a burner for heating the combustion chamber, passages for the combustion products from said chamber through the space above said reservoir to the said pipe connection, a conduit from said compressed air conduit to said burner, a pipe carrying liquid fuel through the combustion chamber to the reservoir, and a pipe from the compressed air conduit to said liquid carrying pipe for returning

condensed fuel from the compressed air conduit, said condensate pipe being U-shaped at the bottom to form therein a liquid seal.

14. In a liquid fuel vaporizing device in combination, a generator divided into an upper vaporizing chamber having a reservoir therein and a lower combustion chamber, a conduit for air under pressure, pipe connection from said upper chamber to said conduit, a butterfly valve in the pipe connection, a burner below the generator for heating said combustion chamber, passages for the combustion products through the space above said reservoir to the said pipe connection, and a conduit from said compressed air conduits to the burner.

15. In a liquid fuel vaporizing device in combination, a generator divided into an upper vaporizing chamber having a reservoir therein and a lower combustion chamber, a conduit for air under pressure, pipe connection from said vaporizing chamber to said conduit, a butterfly valve in said pipe connection, a burner below the generator for heating the combustion chamber, passages for the combustion products through the space above said reservoir to the pipe connection, a conduit from said compressed air conduit to the burner, a pipe carrying liquid fuel through the combustion chamber to the reservoir, and means associated with said liquid fuel pipe for controlling the liquid level within the reservoir.

16. In a liquid fuel vaporizing device in combination, a generator divided into an upper vaporizing chamber having a fuel reservoir therein and a lower combustion chamber, a conduit for air under pressure, pipe connection from the vaporizing chamber to said conduit, a burner below the generator for heating the combustion chamber, and conduits from the combustion chamber to the space above the reservoir for carrying the combustion products across the surface of the liquid within the reservoir to said pipe connection.

17. In a liquid fuel vaporizing device in combination, a generator divided into an upper vaporizing chamber having a liquid fuel reservoir therein and a lower combustion chamber, a conduit for air under pressure, pipe connection from said vaporizing chamber to said conduit, a burner below the generator for heating the said combustion chamber, passages from the latter to the space within the vaporizing chamber above said reservoir, said passages terminating at the top in lateral outlets for carrying the combustion products along the surface of the liquid fuel within the reservoir to said pipe connection, nozzles in said outlets drawing vaporized fuel from above the surface of the liquid within the reservoir, and an annular baffle plate extending horizontally into the space within the combustion chamber from said burner, the lower ends of said passages being seated in and extending through said plate.

18. A liquid fuel vaporizing device including a generator divided by a horizontal partition into an upper vaporizing chamber and a lower combustion chamber, a burner rising into said combustion chamber, said burner having an annular baffle plate extending from the top thereof parallel with said partition, means carrying liquid fuel through the combustion chamber and the partition to form a pool on top thereof within the vaporizing chamber, and passages for the combustion products rising through the baffle plate

and the partition, said passages terminating at the top in laterally directed nozzles.

19. A liquid fuel vaporizing device including a generator divided by a horizontal partition into an upper vaporizing chamber and a lower combustion chamber, the center of said partition being recessed to form a dome rising into the upper chamber, a burner rising into said combustion chamber, said burner having an annular baffle plate extending from the top thereof parallel with said partition, means carrying liquid fuel through the combustion chamber and the partition into the vaporizing chamber to form a pool about said dome on top of the partition, conduits rising through the baffle plate and the partition, said conduits having lateral outlets at the top and nozzles seated in said outlets, said nozzles having downwardly directed portions forming inlets directly above the surface of the pool.

20. A liquid fuel vaporizing device including a generator divided by a horizontal partition in the upper vaporizing chamber and a lower combustion chamber, the center of said partition being recessed to form a dome rising into the upper chamber, a burner rising into the combus-

5
10

tion chamber, said burner having an annular baffle plate laterally extending from the top thereof parallel with said partition, means carrying liquid fuel through the combustion chamber and the partition to the vaporizing chamber to form a pool therein, conduits rising through the baffle plate and the partition, said conduits having lateral outlets at the top thereof, annular plugs seated in said outlets for axial adjustment therein, and nozzles seated in said outlets and extending into said plugs, the nozzles having downwardly directed portions forming inlets directly above the surface of the pool.
